UNITED STATES PATENT OFFICE

ROLLIN ABELL, OF MILTON, MASSACHUSETTS

ENGINE STARTER

Application filed September 30, 1924. Serial No. 740,728.

This invention relates to starters for internal combustion engines, and especially to starters of the type in which a starting pinion is shifted into gear and rotated by an 5 axially movable and rotatory transmission device.

One object of the invention is to provide improved means for softening the application 10 of the operating torque to the starting pinion, and another is to provide for softening the axial movement by which the pinion is shifted into gear, so that neither the pinion nor its shifting mechanism will be subjected 15 to a violent shock or impact either when starting it toward or arresting it at its operative position.

A feature of the invention consists in a 20 rotary and axially movable transmission unit arranged to shift a starting pinion axially to an operating position, this unit also serving to drive the pinion and including, for this purpose, a pair of cooperative camming members one of which has a camming surface of 25 graduated pitch the steepest portion of which is within the angle of repose. The effect of this camming couple is to develop the operating torque gradually so that no sudden shock or impact will occur at the instant of initiating rotation of the starting pinion whether 30 the load be light or heavy. This camming couple is preferably supplemented by a spring arranged to resist the camming action and thereby spread the development of the operating 35 torque over a greater range of camming motion than if spring resistance were omitted.

Another feature of the invention consists 40 in improved means for shifting the starting pinion axially into gear with a gradually diminishing speed in the latter stages of movement. As shown, this feature is provided by a rotatory cam member having duplicate cam surfaces of graduated pitch for producing the axial shifting movement of the starting pinion, said cam surfaces, unlike those in prior 45 constructions, being curved to decelerate the speed in the latter stages of shifting movement.

As shown, the aforesaid cam member is 50 provided with "high spots" formed and arranged to perform another novel function, viz,

to maintain the starting pinion in its operative position in case of momentary relief of the starting torque caused by an incompletely starting of the engine.

Although the duplication of the aforesaid 55 cam surfaces and high spots is preferable for the sake of balance and ease of operation, the principles of the invention are not limited to this duplicate construction.

Still another novel feature, but one which 60 relates to the cam surfaces above mentioned, consists in a curve for developing a gradually accelerative axial movement during the early 65 stages in combination with the aforesaid curve for decelerating such movement during the latter stages. This double effect, which I 70 consider broadly new, is conveniently obtained by cam surfaces of ogee curvature, and may be developed to an extent that will produce acceleration from zero degree to a maximum degree and deceleration from said maximum degree to the zero degree. Thus, the 75 action of the operating member is soft and gentle in the initial stages to start the axial movement of the pinion as well as in the latter stages to arrest such movement, and it is to be observed that these desirable effects are produced without a spring. So far as I am aware 80 no prior construction has had an operating member that functions with a decelerating effect as the pinion approaches its working position.

An advantage of incorporating the first-mentioned camming couple into the axially movable transmission unit is that its effect is 85 segregated from that of the camming couple that produces the axial shifting movement. Consequently, the reaction of the camming surface of the first-mentioned couple cannot disengage the pinion from the driven gear 90 of the engine, that result being exclusively under the control of the camming couple that shifts the pinion to its operative position. In consequence of thus segregating the two camming couples it is possible to form the camming surfaces of the two couples according to 95 the requirements of each of them without any limitation due to the other.

Preferably, and as herein shown, the two 100 camming couples are so designed and related

that only three parts are required to fill their quota of elements. That is to say, one of the three parts serves not only as a member of one of the camming couples but also serves as a member of the other camming couple. This feature is of considerable practical value, inasmuch as it avoids complexity of structure, effects a saving in manufacturing cost, facilitates assembling the parts and insures durability under heavy operating stresses.

Other features of the invention are herein-after described and claimed and are illustrated by the drawings.

Referring to the drawings,

Figure 1 is a side elevation of a starting mechanism embodying the invention in a form which I consider preferable, and includes broken lines representing portions of a starting motor and a gear of an internal combustion engine.

Figure 2 is a longitudinal section of the starting mechanism.

Figure 3 is a development of the operating member of the mechanism.

Figure 4 is an elevation of the clutch members that develop the operating torque gradually.

Figure 5 is an end elevation of the members shown in Figure 4.

Figure 6 is an elevation of a disconnectible releasing clutch by which rotation is transmitted to the stationary pinion.

Referring to Figure 1, a portion of the casing of an electric starting motor is represented at 10, and the armature shaft at 11. A spur gear 12, shown by broken lines, represents the gear usually formed on or fastened to the flywheel of an engine. The motor shaft 11 projects a few inches from the casing 10 to carry the starting mechanism and is held against axial movement by any suitable means, not shown.

The operating member of the starting mechanism is indicated at 14 and is fastened to the shaft 11 by a set-screw 15. This member is a cylindric shell and is formed with duplicate cam slots 16 diametrically opposite to each other to receive lugs or stud portions 17 formed on a collar 18. The surfaces that form the slots 16 have ogee curvature, both end portions of each slot being substantially tangential to planes at right angles to the axis of rotation. These planes are offset from each other by a distance necessary to shift the starting pinion into and out of gear, and the slots are formed to develop the axial movement with an accelerative effect from the zero degree to the maximum degree during the first half of the total range of axial movement and to effect deceleration from the maximum degree to the zero degree during the second half. The slots are open at 19 to permit assembling the parts, and the surfaces 20 extending parallel to the axis of rotation to provide driving abutments by which the op-

erating torque is applied to start the engine. It is to be noted that the lug 17, after reaching the high spot of the cam as shown in Figure 3, is still a considerable distance from the driving abutment 20, and that the surface 16* on which it runs thereafter has no appreciable "rise" or camming action. This idle surface 16* functions, as hereinafter explained, to prevent demeshing of the pinion in case of a momentary relief of the starting torque caused by an incomplete starting of the engine.

The collar 18 surrounds a sleeve 21, these two members forming a novel type of resilient clutch, being telescopically related and having relative axial movement and relative rotary movement, both slight, to provide for a gradual development of the starting torque. The driving connection between them is provided by diametrically opposite lugs or stud portions 22 formed on the sleeve, and semi-circular concave cam surfaces provided by notches 23 formed in the collar to receive them.

The sleeve 21 is arranged to slide axially on the motor shaft 11 and the two are capable of relative turning movement. A starting pinion 24 surrounds the sleeve 21 and these two also are capable of relative axial movement and turning movement. An outer sleeve 25 screwed on the sleeve 21 confines the pinion and is elongated to bear in the motor casing 10 which, as shown, provides a journal for it. A compression spring 26, under initial compression between the pinion and the collar 18, keeps the latter against the studs 22 and keeps the pinion against the sleeve 25. The abutting ends of the pinion and sleeve are formed with cooperative clutch teeth 27 by which rotation is transmitted from the sleeve to the pinion to start the engine. The driving surfaces of these teeth are inclined to the axis of rotation to prevent the development of torque above a degree that can safely be imposed upon the mechanism. If the engine backfires or fails to respond when the starting mechanism is operating, the driving connection between the pinion and the clutch-sleeve is automatically ruptured by the reaction of the inclined driving surfaces and the teeth of the sleeve click over those of the pinion without unduly straining the mechanism.

Referring to Figures 2 and 4, the driving connection between the collar 18 and the sleeve 21 is designed to develop the starting torque gradually so that the action of the mechanism on the engine gear 12 will be soft without sacrificing power. When the collar 18 starts to turn, the load on the sleeve 21 causes the collar to gain relatively to the sleeve. Then the reaction of the studs 22 on the curved surfaces that form the notches 23 develops the torque gradually and with a rapidly increasing ratio, assisted by the com-

5 pressure spring 26 which resists the relative axial movement caused by the relative turning movement. As the steeper portions of the curved surfaces come into contact with the studs 22 the torque is developed to a degree so nearly positive that it turns the clutch sleeve 25 in any event. If the engine gear 12 responds the pinion 24 and sleeve 25 will remain in clutched relation and turn as one, but if the load on the engine gear is abnormally great the inclined driving faces of the clutch teeth 27 will, by their reaction, repel the pinion against the force of the spring 26 and permit the sleeve 25 to rotate while the pinion remains locked with the engine gear.

10 The illustrated construction is such that the collar 18, sleeve 21 and sleeve 25 constitute an axially movable and rotatable transmission unit by which the starting pinion is shifted axially and rotated. Furthermore, the conjoint actions of the collar 18, sleeve 21 and spring 26 provide a softening effect on the starting action, while the softening effect upon the axial shifting is afforded 15 by the novel form of the cam surfaces in the operating member 14.

15 A spring 30 is preferably arranged to oppose axial movement of the transmission unit to its operative position. For this purpose the starting shaft 11 is formed with a shoulder 31 to provide an abutment for the spring, and the sleeve 25 is formed with an internal abutment 32. The spring is initially relaxed and the space between the abutments 31, 32 is greater than the normal length of the spring by a distance greater than that necessary to shift the pinion into meshed relation with the gear 12.

20 In operation, the pinion goes in gear before the sleeve 25 begins to compress the spring 30, but during the latter stages of axial movement of the transmission unit the said spring will undergo compression and such axial movement on the part of the transmission unit will cease when the abutments 20 and lugs 17 are in or near the relation shown in Figure 3. Here, it is to be assumed that the operating member 14 is moving in the direction indicated by an arrow.

25 When the spring 30 is compressed by shifting the transmission unit to its operative position it takes up loose play in the parts and reduces the noise caused by the impact of the driving abutments 20 against the lugs 17. Moreover, the pressure of the lugs 17 against the non-inclined surfaces 16^x, due to the deflection of the spring 30, develops a considerable factor of friction which resists the return of the lugs 17 to the inclined cam surfaces. This latter effect is not sufficient to prevent the lugs from returning to their initial positions in the cam slots whenever a successful starting of the engine is accomplished, but it is sufficient to prevent de-

30 pleted starting of the engine, as, for example, when an explosive impulse in but one cylinder of the engine produces a rotary impulse but is not followed immediately by impulses in the other cylinders. Thus, the non-reactive arrangement of the surfaces 16^x, supplemented by their frictional resistance above referred to, keeps the pinion in mesh until regular operation of the engine is effected.

35 When the starting mechanism is not operating, the parts occupy the positions shown in Figures 1 and 2. By energizing the starting motor, represented by the element 10, the shaft 11 is caused to turn in the direction indicated by arrows in Figure 1. The inertia of the transmission unit holds the latter against rotation while the cams 16 shift the pinion into gear. Rotation of the collar 18 will begin when the abutments 20 strike the lugs 17, whereupon the curved surfaces 23 of said collar will function to develop the starting torque by their creeping action on the lugs 22, the spring 26 now acting in conjunction with the surfaces 23 to build up the starting torque.

40 Assuming that the engine responds to the starting action by operating under its own power, it will drive the gear 12 at a speed greater than that developed by the starting mechanism and this will cause the transmission unit to advance relatively to the operating unit. Consequently, the lugs 17 will move ahead in the cam slots 16 with the result of shifting the pinion out of gear and back to its initial position as shown in Figures 1 and 2.

45 What I claim is:

1. An engine-starter comprising a starting pinion, and a rotary and axially movable unit arranged to shift said pinion axially and impart rotation thereto, said unit comprising two relatively movable clutch members and a spring arranged to maintain them normally in one relation, one of said clutch members having a lug and the other having a semi-circular concave cam face for cooperating with said lug to develop the operating torque gradually from a low degree to a high degree.

50 2. An engine-starter comprising a starting pinion, a rotary but axially stationary operating member, and a rotary and axially movable unit arranged to shift said pinion axially and transmit rotation thereto from said operating member, the operating connection between said operating member and said unit including a cam face of gradually diminishing pitch to shift said unit axially with a decelerating speed.

55 3. An engine-starter comprising a starting pinion, a rotary but axially stationary operating member, and a rotary and axially movable unit arranged to shift said pinion axially and transmit rotation thereto from said operating member, the operating con-

nection between said operating member and said unit including a cam face of ogee curvature to develop axial movement initially with accelerating speed and thereafter with decelerating speed.

5. An engine-starter comprising a starting pinion, a rotary but axially stationary operating member, and a rotary and axially movable unit arranged to shift said pinion axially and transmit rotation thereto from

10 said operating member, the operating connection between said operating member and said unit including a cam face, one portion of which is curved to develop axial movement with accelerating speed and the other 15 of which is otherwise curved to decelerate the axial movement.

15. An engine-starter comprising a starting pinion, a rotary but axially stationary operating member, and a rotary and axially movable unit arranged to shift said pinion axially and transmit rotation thereto from said operating member, the operating connection 20 between said operating member and said unit including a cam face having successive portions one of which is curved to develop 25 axial movement accelerating to a maximum degree and the other of which is otherwise curved to diminish the axial movement gradually from said maximum degree to zero 30 degree.

35. An engine-starter comprising a starting pinion, a rotary but axially stationary operating member, and a rotary and axially movable unit arranged to shift said pinion axially and transmit rotation thereto from 40 said operating member, said operating member being hollow and having a cam surface to impart the axial movement to said unit, and said unit including relatively movable members nested in said operating member 45 and organized to develop the operating torque gradually.

45. An engine-starter comprising a starting pinion, a rotary but axially stationary operating member, and a rotary and axially movable unit arranged to shift said pinion axially and transmit rotation thereto from 50 said operating member, said operating member being hollow and having a cam surface to impart the axial movement to said unit, and said unit including a collar nested in 55 said operating member and a supporting member on which said collar is arranged to turn and slide, said collar having a lug or 60 follower to cooperate with said cam surface and having a curved driving surface, and said supporting member having a lug arranged to cooperate with said curved driving 65 surface to develop the operating torque gradually.

60. An engine-starter comprising a rotary but axially stationary operating member consisting of a hollow barrel cam, a rotary and axially movable unit, and a starting pinion

carried by said unit, said unit including two telescopically related members nested in said operating member, one of said telescopically related members having a connection with said operating member by which it is shifted axially and rotated, and said telescopically related members having cooperative portions by which the starting torque is developed gradually and transmitted to drive said pinion.

70. 9. An engine starter comprising a rotary operating unit, a rotary and axially movable transmission unit provided with a starting pinion, and a spring arranged to oppose axial movement of said transmission unit to its operative position, one of said units having a driving lug and the other having a driving abutment and a cam surface leading thereto for cooperating with said lug, said cam surface terminating adjacent to said driving abutment in a portion arranged to maintain 75 said transmission unit in its operative position in case of momentary relief of the starting torque caused by an incompletely starting of the engine.

80. 10. An engine starter comprising a rotary operating unit, a rotary and axially movable transmission unit provided with a starting pinion, and a spring arranged to oppose axial movement of said transmission unit to its operative position, one of said units having a driving lug and the other having a driving abutment and a cam surface leading thereto for cooperating with said lug, said cam surface terminating adjacent to said driving abutment in a portion at right angles to the axis of rotation whereby said transmission 85 unit is maintained in operative position in case of momentary relief of the starting torque caused by an incompletely starting of the engine.

90. 11. In an engine starter, a rotary and axially movable transmission sleeve provided with a pinion and a lug, an axially movable collar arranged on said sleeve to form a lost motion driving connection with said lug, a compression spring arranged on said sleeve to maintain said collar against said lug, said collar having a concave camming surface engaging said lug to compress said spring and thereby balance the torque and the load, and means arranged to shift said collar axially and drive it.

110. 12. In an engine starter, a rotary and axially movable transmission sleeve provided with a driving lug and an abutment spaced apart axially, a driving collar and a pinion arranged on said sleeve between said lug and said abutment, and a compression spring between and abutting said collar and said pinion, said abutment and said pinion having cooperative clutching surfaces forming an overrunning clutch, and said collar having a concave camming surface engaging said lug to compress said spring and thereby balance 115
